United States Patent Office

Des. 180,613
Patented July 9, 1957

180,613

CHILD'S SEWING MACHINE

Johannes Neukirch, Bad Durkheim, Pfalz, Germany, assignor to G. M. Pfaff A.-G., Kaiserslautern, Pfalz, Germany

Application July 13, 1956, Serial No. 42,245

Term of patent 14 years

(Cl. D34—15)

FIG. 1.

FIG. 2.

FIG. 3.

FIG. 4.

Figure 1 is a one-quarter front perspective view of a child's sewing machine showing my new design;

Figure 2 is a one-quarter rear perspective view thereof;

Figure 3 is an end perspective view of the child's sewing machine toy taken from the left side of Figure 1; and

Figure 4 is an end perspective view thereof taken from the right side of Figure 1.

I claim:

The ornamental design for a child's sewing machine, substantially as shown.
